UNITED STATES PATENT OFFICE.

ORVILLE C. MANN, OF OAK PARK, ILLINOIS.

VENTILATOR.

1,313,401.

Specification of Letters Patent. Patented Aug. 19, 1919.

Application filed February 5, 1918. Serial No. 215,439.

To all whom it may concern:

Be it known that I, ORVILLE C. MANN, a citizen of the United States, residing at Oak Park, in the county of Cook and State 5 of Illinois, have invented new and useful Improvements in Ventilators, of which the following is a specification, reference being had to the accompanying drawings, forming a part thereof.

10 The purpose of this invention is to provide an improved device of the nature of a window ventilator, that is, a device adapted to be mounted in a window opening for ventilating the apartment to which the 15 window pertains. It consists in the elements and features of construction shown and described in the drawings as indicated in the claims.

In the drawings:—

20 Figure 1 is a vertical section through the wall of a room and window casing therein which is equipped with a device embodying this invention, the device itself being shown in transverse vertical section.

25 Fig. 2 is a section at the line 2—2 on Fig. 1.

Fig. 3 is a section at the line 3—3 on Fig. 1.

30 Fig. 4 is a detail section of the lower bar of the sash equipped with a device constituting a modification of one feature of this invention.

35 Fig. 5 is a detail section in the same plane as the section of Fig. 2, showing one corner 35 of the box and the window stop to which it is secured, provided with a spacing plate.

40 In the drawings a window casing of common construction for a vertically sliding sash is shown at 1, the lower side bar of the casing being shown at 2, extending outwardly with an inclined upper face as shown at 2^a, forming the outer or weather sill; 3, is the inner sill behind which the lower vertical sliding sash shuts; 4, is said sash shown 45 partly elevated for use of the ventilator.

45 The ventilating device consists of a box, 5, preferably constructed of sheet metal as illustrated, having one vertical side open substantially the whole length of the box, 50 and the whole width except as to the longitudinal upper inner corner member, 6, of the box, and having the top open the whole length, and the entire width except as to so much as is occupied by said upper inner 55 longitudinal corner member, 6. The ends, 7, 7, of the box are connected by said cor-

ner member and by the back or bottom member 7^b, which is inclined upwardly and inwardly and curved concave inwardly, that is, toward the cavity of the box, 60 as seen in Fig. 1. The longitudinal side opening, 8, is provided with a closure, 9, which is hinged to the lower inner longitudinal corner of said longitudinal corner member, 6, and swings down inwardly from 65 its open position, shown in full line in Fig. 1, to its closed position, shown in dotted lines in said figure. Said closure is connected with said corner member, 6, by spring hinges, 10, 10, of usual construction adapted 70 by their springs to uphold said closure at the open position shown in Fig. 1, and at that position it is stopped in the lower edge of the corner member, 6, which is beveled or formed with its lower edge in a 75 plane inclined slightly downward and outward, the inclination corresponding and conforming to the customary inclination of the outer sill, 2, and of the beveled lower edge of sash, 4, which seats on said inclined sill. By reason of this inclination of the closure, 9, at its open position it serves as a deflector for rain falling when the closure is open, preventing it from draining 80 back into the box. It will be understood 85 that the closure by reason of its inclination is intended to prevent rain driving into the box even when the closure is open, and of course to exclude water from the box when the closure is closed. The top opening at 12, is provided with a screen cover, 13, hinged at its inner edge to the upper side of said corner member, 6, and stopped when closed by an inturned flange, 7^a, extending along the upper margin of the back 90 member, 7^b. Preferably, the corner member, 6, is made of considerable width, amounting in practice to about an inch, so that the closure, 9, hinged at the inner lower longitudinal corner of said corner 100 member may be readily operated by the sash, 4, in the closing movement of the latter for closing said closure by the encounter of the lower inner corner of the sash with the upper outer surface of said closure at 105 a sufficient distance from its hinge to afford adequate leverage for closing it against resistance of the spring hinges. Preferably, to save the sash from the wear at said corner, which would otherwise directly encounter the closure in said closing operation, round headed screws, 11, may be in- 110

serted in the lower edge of the sash substantially at the forward corner; and the closure, 9, both for the purpose of stiffening it and also to afford a track for the 5 edge of the screws, is formed with transverse grooves, 9^a, fitted to accommodate said round headed screws.

By reason of the concavely curved back, 7^b, of the box, the current of air entering 10 through the device is deflected from horizontal to vertical direction so that it emerges upwardly through the screen cover at the opening in the top of the box. In order to adapt the device to relieve the incoming air 15 to some extent of the dust which it may carry, there is provided a partition or false bottom or back, 16, made of sheet metal with flanges turned on the upper and lower edges for lodging upon and spacing it away from 20 the true back or bottom member, 7^b, forming a pocket or dust receptacle between said back and said false bottom; said false bottom has a multiplicity of apertures, 17, each formed by striking the metal out and folding it up 25 to form a lip 17^a projecting from the upper margin of the aperture, which additionally serves to arrest the dust and causes it to be deflected behind the false bottom and retained in the pocket formed thereby.

30 Instead of the closure member, 9, hinged at the side of the box there may be provided for certain of the functions performed by said closure member a mere deflector plate 18 shown in Fig. 4 secured by screws at the 35 lower edge of the sash, 4, and projecting outwardly at the inclination of said lower edge, and preferably at its outer edge having a flange, 18^a, turned downwardly, the width of said plate being sufficient to cause it at 40 the closed position of the sash to completely cover the exposed surface of the outer sill, 2, thereby, besides its other functions, serving as a protection against fire from sparks which might be lodged on the wooden sill. 45 It will be seen that this plate performs the functions of deflecting the rain and guarding the ventilator against access of rain thereto, and also that in this form of the device as in that shown in Figs. 1 and 2, the 50 ventilator is automatically opened and closed by the opening and closing of the sash.

It will be noticed that the back member, 7^b, is flanged downwardly at its lower edge 55 for engagement against the outer edge of the sill, 3, thus making the device serve as a protection against in-driving rain whether the sash is closed or open, and the inclined position of the back member, 7^b, will cause 60 any water which may drive into the box to drain out immediately, even though it might drive in so far as to pass through one of the apertures, 17, in the false bottom, the lower flange, 17^b, of that false bottom having 65 notches in its lower edge, one of which is

shown at 17^c, to permit the escape of any water which may be driven into the dust pocket.

For convenience in fitting these ventilators to windows of all widths, they will of course 70 be made in a plurality of sizes; but to reduce the number of different sizes required, the unit differences in length between consecutive sizes may be, say, three or four inches, and the flange, 7^d, at the outer edge of each 75 side plate, 7, will then be made two or three inches wide and may be trimmed off with shears to reduce the total width including the flanges to that of the casing which is to be fitted. When the nearest size available 80 for a given casing is such that a space would remain between the side plate, 7, and the side stop or sash-retaining strip, 14, of the casing, so that a screw, as 15, for securing the device would not bind the plate, 7, against 85 the side stop, there will be employed a filler plate, 20, having flanges, 20^a, turned up on two adjacent edges and provided with rivet holes for securing it to the side plate, 7, and its flange, 7^d, as seen in Fig. 5; and this 90 filler plate will be provided along the inner edge with a series of screw holes, 20^b, at distances from center to center not more than the usual thickness of the side stop, 14. This filler plate will be trimmed to the same 95 width as the flange, 7^d, inserted under the end of the side stop, 14, (first removed and trimmed for the purpose), and secured by a screw through the outermost hole left standing after trimming the filler plate, engaging 100 it securely with the sill.

I claim:—

1. In combination with a window casing and a vertically sliding sash therein, a box approximating in length the width of the 105 sash opening in the casing, having openings extending longitudinally in one vertical side and in the top, said box having a removable partition extending longitudinally and inclined upwardly from the lower side 110 of the opening in the lower side of the box toward the inner side of the opening in the top of the box, and having apertures each provided with a lip extending inwardly from its upper margin.

2. In combination with a window casing, a ventilator box for mounting at the sash opening having openings extending longitudinally in one vertical side and in the top, having a third longitudinal side extending 115 obliquely with respect to the top and outer side, and a removable false back or partition extending longitudinally of the box and provided with marginal flanges by which it is lodged upon and spaced inwardly 120 from said inclined back of the box, said false back or partition having apertures each provided at its upper margin with an inwardly-extending lip whereby there is formed a dust-receiving pocket into which 125

130

the dust from the in-coming air current is deflected.

3. In combination with a window casing, a ventilator box for mounting at the sash opening, having a longitudinally extending opening in the outer vertical side, the box comprising a longitudinal corner member at the junction of the side and top; a closure for said opening in the vertical side hinged 10 to said corner member at the lower inner

corner of said member, and adapted to swing upward and outward through said opening and be stopped against the under side of said corner member at a position extending outwardly and downwardly. 15

In testimony whereof, I have hereunto set my hand at Chicago, Illinois, this 31st day of January, 1918.

ORVILLE C. MANN.
